UNITED STATES PATENT OFFICE.

GEORGE ALFRED BONELLI, OF KINGMAN, ARIZONA TERRITORY.

HYDROCARBON-BURNER.

SPECIFICATION forming part of Letters Patent No. 693,225, dated February 11, 1902.

Application filed March 5, 1901. Serial No. 49,772. (No model.)

To all whom it may concern:

Be it known that I, GEORGE ALFRED BONELLI, a citizen of the United States, and a resident of Kingman, in the county of Mohave, 5 Territory of Arizona, have invented a new and Improved Hydrocarbon-Burner, of which the following is a full, clear, and exact description.

The object of the invention is to provide a 10 new and improved hydrocarbon-burner which is simple and durable in construction, very effective in operation, and arranged to insure a perfect vaporization of the liquid fuel and a complete combustion of the gas produced 15 to form a very bright steady light for illuminating, as well as for heating and other purposes, without necessarily requiring a mantle, chimney, or the like.

The invention consists of novel features and 20 parts and combinations of the same, as will be fully described hereinafter and then pointed out in the claims.

A practical embodiment of the invention is represented in the accompanying drawings, 25 forming a part of this specification, in which similar characters of reference indicate corresponding parts in all the views.

Figure 1 is a side elevation of the improvement as applied. Fig. 2 is an enlarged sec- 30 tional side elevation of the improvement, and Fig. 3 is a transverse section of the same on the line 3 3 in Fig. 2.

The supply-pipe A is connected with a suitable tank or other receptacle B, containing 35 liquid fuel, and on said supply-pipe A is screwed or otherwise secured the end C' of a casing C, forming part of a hydrocarbon-burner, said end C' containing a screen D for preventing the impurities contained in the 40 liquid from passing into the burner. The casing C, adjacent to the screen D, is provided with a valve-seat C², adapted to be engaged by a needle-valve E, having its threaded stem E' screwing in the correspondingly-threaded 45 portion C³ of the burner-casing C, said stem extending through a stuffing-box F to the outside of the burner and carrying at its outer end a handle E² under the control of the operator for operating the valve E to control 50 the amount of liquid fuel passing from the

supply-pipe A into the burner-casing and to the burner or to completely shut off the supply whenever desired.

In the burner-casing C behind the valve E screws the threaded shank G' of a combined 55 gas generator and spreader G, preferably made comparatively flat and approximately semicircular in shape, as illustrated in the drawings, the peripheral edge tapering from opposite sides to form a blunt edge, as indicated in Fig. 3. This combined gas generator and spreader is formed with a peripheral passage G², which opens at its bottom into the hollow shank G' to allow the liquid fuel to pass up into said passage G² to be vaporized therein, 60 as hereinafter more fully described. The upper end of the passage G² leads into a downwardly-extending passage G³, terminating a distance above the bottom of the passage G², and into the opposite sides of the generator and 65 spreader G are screwed or otherwise fastened the burners H, opening into the bottom of said central passage G³. The burners H extend transversely from the opposite sides of the combined generator and spreader, and 70 each is formed with a passage H², connecting at the inner end with the passage G³ and terminating at the outer end in an inclined slot H², extending in the direction of the corresponding side of the generator and spreader 75 G, as will be readily understood by reference to Fig. 3. Now when the burner is in action the flames issuing from the slots H² of the burners H strike the sides of the generator and spreader G, so as to heat the same and 80 cause a vaporization of the liquid fuel passing through the passage G² from the casing C by way of the shank G'. The gas thus generated passes from the passage G² into the passage G³ and to the two burners H, in 85 which the gas is burned. When the flames strike the generator and spreader G at the sides thereof and at an angle, the flames are spread and finally unite at the peripheral edge of the combined generator and spreader 90 G and extend as a single flame from said edge. By the arrangement described complete combustion of the fuel is insured and an exceedingly bright and steady flame is 95 produced for illuminating, heating, and other 100

purposes without requiring a chimney, mantle, or the like, as no smoke or odor whatever is produced.

The amount of liquid fuel passing to the casing is controlled by the valve E, as previously described, and the burner may be completely shut off from the supply by manipulating the handle E² correspondingly to close the valve E. A screen I is preferably placed in the lower end of the shank G' to positively prevent impurities from passing to the burners in case such impurities should have passed through the screen D.

The generator and spreader G may be made of metal, clay, or other suitable material.

I do not limit myself to the particular construction described, as the same may be varied without deviating from the spirit of my invention, nor do I limit myself to the particular application of the device as shown and described.

Having thus fully described my invention, I claim as new and desire to secure by Letters Patent—

25 1. A hydrocarbon-burner, comprising a plurality of burners, and a combined gas generator and spreader approximately flat and having its periphery arranged in a vertical plane, the opposite sides tapering toward the periphery, the said gas generator and spreader extending between the burners and the openings of the latter extending in the direction of the sides of the generator and spreader, for the flames of the burner to heat said generator and spreader and thereby insure vaporization of the liquid fuel and cause the flame issuing from the burners to spread separately and to be united at the edge of the generator and spreader, as set forth.

40 2. A hydrocarbon-gas burner comprising a combined gas generator and spreader approximately flat and semicircular in shape and having its opposite sides tapering toward its periphery, the said periphery being arranged 45 in a vertical plane, a plurality of burners, between which the generator and spreader extend, the said burners being arranged to direct the flames upon the tapering sides of the generator and spreader to heat the same and thereby insure vaporization of the liquid fuel and cause the flame issuing from the burners to spread separately and to be united along the edge of the generator and spreader, and a valve for closing the fuel-supply to said 50 combined generator and spreader, as set forth.

55 3. A hydrocarbon - burner, comprising a gas-generator approximately semicircular in shape and having flat sides tapering toward the periphery, the periphery being arranged 60 in a vertical plane, the said generator being formed with an interior circumferential pas-

sage for the fuel, and a central passage leading from the circumferential passage, a casing carrying said generator and connected with a fuel-supply, and burners extending 65 from opposite sides of said generator and opening into the said central passage, the said burners being arranged to direct their flames against the sides of the gas-generator to spread the flames lengthwise of the generator and to 70 cause the flames to meet and join along the periphery of the generator, as set forth.

4. A hydrocarbon-burner, comprising a gas generator and spreader approximately flat and semicircular in shape, and formed with 75 an interior circumferential passage and a central passage leading from the top of the circumferential passage, and burners secured to the sides of said gas generator and spreader and opening into said central passage, said 80 burners having angular slots extending in the direction of the flat sides of said gas generator and spreader, as set forth.

5. A hydrocarbon-burner, comprising a gas generator and spreader approximately flat 85 and semicircular in shape and formed with interior circumferential passage and a central passage, burners secured to the sides of said gas generator and spreader and opening into said central passage, said burners having angular slots extending in the direction 90 of the flat sides of said gas generator and spreader, a casing into which screws the hollow threaded shank of the generator and spreader, the shank opening into the bottom 95 of the circumferential passage, and a valve controlling the inlet of the liquid fuel to said casing, as set forth.

6. A hydrocarbon-burner comprising a gas-generator approximately flat and semicircular 100 in shape and formed with an interior continuous circumferential passage, and a central passage leading from the top of the circumferential passage and terminating above the lower portion of said circumferential passage, a casing carrying said generator and connected with a liquid-fuel supply, the said casing communicating with the lower portion 105 of the circumferential passage in the generator, burners extending from opposite sides of said generator and having their openings arranged to direct the flames against the sides of the generator, and a valve controlling the inlet of the fuel to said casing as set forth.

In testimony whereof I have signed my 115 name to this specification in the presence of two subscribing witnesses.

GEORGE ALFRED BONELLI.
